UNITED STATES PATENT OFFICE.

JOHN H. LEE, OF CHICAGO, ILLINOIS.

GAME APPARATUS.

No. 888,837.

Specification of Letters Patent.

Patented May 19, 1908.

Application filed November 29, 1905. Serial No. 289,586.

To all whom it may concern:

Be it known that I, JOHN H. LEE, a citizen of the United States, residing at Chicago, in the county of Cook and State of Illinois, have 5 invented a new and useful Improvement in Game Apparatus, of which the following is a specification.

My invention relates particularly to bowling alleys; and my primary object is to provide a construction enabling the game of bowling to be played upon a shorter range than is now necessary, thereby enabling the apparatus to be installed in places which are not now available for the sport.

15 The invention is illustrated in one embodiment in the accompanying drawing, in which—

Figure 1 represents a longitudinal sectional view of my improved bowling-alley; Fig. 2, a broken plan view of the same; and Fig. 3, a broken vertical section taken as indicated at line 3 of Fig. 1.

In carrying out my invention, I provide a plurality of superposed alleys connected by a curved section, or sections, so that the ball will have transit in one direction and then in the reverse direction on its way to the pins. The number of superposed alleys, and consequently the number of reversals of direction 30 of transit which the ball will undergo in traveling over the course, may be varied at will.

In the preferred construction, I employ a lower going-alley and an upper return-alley, the going-alley being equipped at its rear end 35 with an up-curved section having a forwardly directed free end terminating approximately the space of a ball above the rear end of the return-alley, and the return-alley being equipped at its front end and adjacent to the front end of the going-alley. 40 Such is the construction illustrated, in which A represents the going alley; A¹, the up-curved section forming a continuation of the rear end thereof; B, the return-alley; and B¹, the pit connected with the front end of the return-alley. The going-alley and the up-curved alley-section forming a continuation thereof are flanked by gutters a; and the return-alley is flanked by 45 gutters b located in the same vertical planes as the gutters a. Thus, provision is made for the ball leaving either alley at any point and following through a gutter or gutters to the pit.

I preferably form the device in three sec-

tions, viz: a section a¹ comprising the going-alley proper and the gutters flanking the same; a section a² comprising the up-curved alley-section; and a section b¹ comprising the upper alley, the pit connected therewith and 60 the gutters flanking the upper alley.

The section a¹ may be equipped on its bottom with cross members a³, the rear one of which is thicker than the upper one, whereby the alley A is caused to incline rearwardly 65 and upwardly somewhat. The member a³ projects rearwardly past the rear end of the alley A, and the meeting ends of the alley A and the section A¹ are beveled, the end of the alley A being cut under, whereby a socket is 70 afforded for the adjacent end of the section A¹. When the sections are joined together, they are connected by screws a⁴ passing through the member a³ and into the superposed end of the section A¹. The alley B is 75 equipped with legs b² connected by hinges b³ with the lower side of the alley and adapted to swing inwardly beneath the alley. The lower ends of the legs are equipped with tenons b⁴ which fit into sockets b⁵ with which 80 the lower section a¹ is provided outside of the gutters a. The rear end of the section b¹ is equipped with supports b⁶ for the adjacent portions of the section a². The construction enables the device to be knocked down for 85 purposes of shipment. In this operation, the screws a⁴ are withdrawn, the section a² removed, the section b¹ lifted to separate the legs b² from the section a¹, the legs are then folded inwardly, after which the section b¹ 90 can be dropped upon the section a¹.

The front end of the return-alley is provided adjacent to the pit with spots c to indicate the position of the pins c¹. The front end of the going-alley preferably projects 95 some distance in front of the pit B¹ and is provided with spots c² corresponding in position with the spots c. The spots c² aid the player in placing the ball during delivery. In the playing operation, the player delivers 100 the ball c³ upon the front portion of the alley A, and the ball passes over the alley until it encounters the curved section A¹ when its direction of transit is reversed and it is delivered upon the return-alley B, over which 105 it rolls on its course to the pins. The player is ordinarily able to look over the guards surrounding the pit and see the pins in position, so that it is possible to gage the ball with great accuracy. While the ball is pass- 110

ing over the going-alley A and the curved alley-section A¹, it revolves in one direction; and when it passes on to the return-alley B its direction of rotation is reversed, as indicated by the arrows. Thus, it will be seen that two factors are at work to retard the ball in its course over the alleys and on the way to the pins, namely, the retarding force which comes from the reversal of direction 10 of transit of the ball and the retarding force which comes from the reversal of direction of rotation of the ball. In addition to these retarding forces, I may provide for a buffering force, as by suspending a buffer *d*, from the 15 lower side of the upper alley, the lower edge of the buffer depending within sufficient distance of the upper surface of the lower alley to cause the ball to encounter the buffer as the ball passes over the lower alley. Preferably the buffer is made of some yielding material, such as felt, which will produce a retarding effect upon the ball, without deflecting 20 the ball from its course.

The improved construction renders it possible 25 for full-sized pins and balls to be employed on an alley fifteen or twenty feet in length, and enables the player to exert all the force in bowling that he could exert in playing upon a straight alley of regulation size. Moreover, the construction locates the pins 30 near the bowler, so that the bowler may reset the pins himself, enabling him to dispense with the services of an attendant. It is obvious 35 that the alley may be constructed as a permanent fixture, or it may be made portable in form. In the portable form shown, it is adapted to be placed upon a table, stands, saw-horses, or the like. In the portable form it may be of a very small size to adapt it for 40 use as a toy for children, or a somewhat larger size to adapt it for use as a parlor game for adults, and of a still larger size to adapt it for use in places of public amusement or resort, or for use in the basements or attics 45 of private residences.

It will be understood that the mechanical construction of the device may be varied at will. For instance, where the device is sectionally constructed suitable fittings will be 50 provided for insuring adequate rigidity when the parts are connected. Preferably, the curved alley-section is composed of sheet metal confined by suitable forms, the form of the curved section being approximately that 55 of a half cylinder. While the lower alley is preferably inclined somewhat, so that a ball which fails to pass to the upper alley will return to the starting point, both the lower and the upper alleys have their surfaces perpendicular 60 to a vertical longitudinal plane, and the axis of curvature of the curved section is perpendicular to said plane, *i. e.* the axis of curvature is in a transverse horizontal line. The target, obviously, may be anything desired. For instance, the marks *c* may be 65

simply slight depressions used either to catch the ball or mark the position of the pins, at will.

It is obvious that the pit may be connected with either alley in a construction of the character shown. Moreover, as has been stated, any desired number of superposed alleys may be employed. Changes in details of construction within the spirit of my invention are contemplated, hence no undue limitation should be understood from the foregoing detailed description.

What I regard as new, and desire to secure by Letters Patent, is—

1. The combination of a lower going alley, 80 a curved section connected with one end thereof and forming a continuation thereof, and an upper target carrying or return alley having its rear end presented to the concavity of said curved section, the lower alley having an uninclosed front end projecting in front of the front end of the upper alley. 85

2. The combination of two superposed alleys of approximately equal length, the lower alley constituting the going alley and the upper alley the target carrying or return alley 90 a curved section at one end of the alleys and forming a continuation of one thereof and serving to reverse the direction of transit of the ball and direct the ball from one alley to 95 the other, and a pit at the other end of the alleys connected with the other one thereof, for the purpose set forth.

3. The combination of a going lower alley terminating at the rear end in an upturned 100 curved section having a forwardly directed free end, a return upper alley located below and in front of the free end of said curved section and having its front end terminating near the front end of the lower alley, and a pit 105 connected with the front end of said return alley, space being provided beneath said pit for the passage of a ball on the lower alley.

4. The combination of a lower going alley terminating at the rear end in an up-curved 110 section having a forwardly directed free end, gutters flanking said alley throughout the length thereof, including the curved section, an upper target carrying or return alley located below the level of the free end of 115 said curved section, gutters flanking said upper alley and located in the same vertical plane with said first-named gutters, and a pit connected with the free end of one of said alleys. 120

5. The combination of an inclined lower alley terminating at its rear end in an up-curved section, having a forwardly presented free end, a return-alley located beneath the free end of said curved section within range 125 of a ball passing from the curved section, and a pit connected with the return alley near the free end of the lower alley.

6. The combination of a going-alley of a given length terminating at its rear end in 130

an up-curved section presenting a forwardly directed free end, a shorter return-alley located beneath the free end of said curved section and terminating at its front end slightly in the rear of the front end of the going-alley, and a pit connected with the front end of the return-alley and located above the going-alley and adjacent to the front end thereof, whereby the ball is initially delivered by the player in front of and beneath the pit and returns to the pit in the vicinity of the player, for the purpose set forth.

7. The combination of a lower alley having an up-curved rear end, and an upper alley having its rear end located beneath the free end of the up-curved end of the going-alley, said upper alley being detachably connected with the lower alley, for the purpose set forth.

8. The combination of a going-alley, a superposed upper return-alley equipped at its front end with a pit, a curved alley-section forming a continuation of the lower alley and terminating above the rear end of the return alley, and ball-retarding means above the lower alley, for the purpose set forth.

9. The combination of a lower going-alley, a superposed return-alley, a curved alley-section forming a continuation of the going-alley, a pit connected with the front end of the return-alley, spots on the return-alley adjacent to the pit, and means external to the pit serving to indicate the position of the pins, for the purpose set forth.

10. The combination of a going-alley, a curved alley-section forming a continuation of the going-alley, a return alley terminating near the front end of the going-alley, and targets on the front end of the return alley and near the front end of the going alley.

11. A bowling alley comprising a lower bed having its end remote from the bowler curved upwardly and rearwardly, an upper bed extending into said curvature and below the end thereof and extending back to the bowler and parallel with the lower bed, side and end members on said upper bed affording a pit to receive the pins when struck. 45

12. A bowling alley comprising a lower bed having its end remote from the bowler curved upwardly and rearwardly, an upper bed rigidly connected thereon and extending into said curvature and below the end thereof and back to the bowler and parallel with the lower bed, side and end members on said upper bed affording a pit to receive the ball and the pins when struck. 50 55

13. A bowling alley comprising a lower bed having its end remote from the bowler curved upwardly and rearwardly, an upper bed parallel with the lower bed and extending into said curvature and below the end thereof and back to the bowler, a pit comprising side and end members and a bottom secured at the strike end of the upper bed and adapted to receive the pins when struck. 60 65

14. The combination of a going lower alley terminating at the rear end in an upturned curved section having a forwardly directed free end, a return upper alley located below and in front of the free end of said curved section and having its front end terminating near the front end of the lower alley, and means at the front end of said return upper alley for receiving the ball and holding the same within easy access of the player. 70 75
